(57) **CLAIM**

I claim the ornamental design for a truck camper, as shown and described.

DESCRIPTION

A portion of the disclosure of this patent document contains material to which a claim for copyright is made. The copyright owner has no objection to the reproduction of the patent document or the patent disclosure, as it appears in the U.S. Patent Office records, but reserves all other copyright rights whatsoever.

FIG. 1 is a front, left perspective view of a first embodiment of a truck camper, according to my design;

FIG. 2 is a front view of the truck camper of FIG. 1;

FIG. 3 is a left side view of the truck camper of FIG. 1;

FIG. 4 is a right side view of the truck camper of FIG. 1;

FIG. 5 is a rear view of the truck camper of FIG. 1;

FIG. 6 is a top view of the truck camper of FIG. 1;

FIG. 7 is a bottom view of the truck camper of FIG. 1;

FIG. 8 is a rear, left side perspective view of the truck camper of FIG. 1;

FIG. 9 is a top, left side perspective view of the truck camper of FIG. 1;

FIG. 10 is a front, left side perspective view of a second embodiment of a truck camper, showing my new design;

FIG. 11 is a front view of the truck camper of FIG. 10;

FIG. 12 is a left side view of the truck camper of FIG. 10;

FIG. 13 is a right side view of the truck camper of FIG. 10;

FIG. 14 is a rear view of the truck camper of FIG. 10;

FIG. 15 is a top view of the truck camper of FIG. 10;

FIG. 16 is a bottom view of the truck camper of FIG. 10;

FIG. 17 is a rear, left side perspective view of the truck camper of FIG. 10; and,

FIG. 18 is a top, left side perspective view of the truck camper of FIG. 10.

The broken lines shown in the drawings illustrate portions of the truck camper that form no part of the claimed design.
